UNITED STATES PATENT OFFICE.

SAMUEL P. BUSH, OF COLUMBUS, OHIO, ASSIGNOR TO THE BUCKEYE STEEL CASTINGS COMPANY, OF COLUMBUS, OHIO.

CAR TRUCK.

Application filed September 3, 1926. Serial No. 133,411.

This invention relates to improvements in car trucks of the type shown in an application filed by me July 20th, 1926, Serial No. 123,719, and has special reference to the spring plank. The spring plank is generally a channel member having its flanges extending upwardly or downwardly as may be most convenient or desirable in a given truck, the flanges sometimes being removed 10 at the ends so that the web of the channel is left as a flat plate upon which the springs rest. These channels frequently break. If one side frame assumes a position higher than the other side frame, or if the side 15 frames tend to swing about the journal bearings, as in passing around a curve at speed, certain vertical stresses are set up in the spring plank which it is not well adapted to resist and it, consequently, frequently 20 breaks, usually near the ends. If one side frame rotates in a vertical plane relative to the other side frame, torsional stresses are set up which also contribute to the fracture of the ordinary form of spring plank. If 25 one side frame moves ahead or falls behind the other side frame with reference to the transverse axis of the truck, lateral stresses are set up in the spring plank which contribute to the failure of the plank in service 30 and require that the spring plank be heavy enough to resist them or flexible enough to yield to them without fracture. The objects of the present invention, therefore, are to provide for an improved distribution of 35 load upon the spring plank and the side frame whereby damaging stresses are reduced; to provide a more desirable grouping of springs; to provide a spring plank having a limited flexibility and better adapted 40 to meet the stresses developed in service, and to promote convenience and reduce labor in assembling and disassembling the parts of the truck. These objects are attained in the structure illustrated in the accompanying 45 drawings and the invention resides in certain novel features hereinafter first fully described and then particularly pointed out in the appended claims.

In the drawings, Figure 1 is a side elevation, partly broken away and in section, 50 of a truck embodying the invention;

Figure 2 is a view of the same partly in top plan and partly in horizontal section;

Figure 3 is a vertical section taken longitudinally of the spring plank;

Figure 4 is a view similar to Figure 3 showing an alternative construction.

The side frame is cast in one integral structure having an upper and compression member 1, a lower tension member 2, and columns 3, these several members defining a central opening through which the ends of the bolster and the spring plank are received. The opposed sides of the columns 60 have their lower portions projected within said opening in downwardly converging relation, as at 4, and the lower portion of the tension member is concave, as indicated at 5. A spring seat 6 is formed on the tension member at the base of each column, said seat defining a shoulder 7 having approximately the same level as the top of the spring 65 plank.

The spring plank consists of end portions 75 8, which are skeletonized castings, and a central portion 9 connecting the end castings and which may be a rolled steel bar of rectangular cross section or a light weight channel or I section. The end castings are convex on their under sides to conform to the contour of the upper surface of the side frame at the center of the bolster opening and the upper surfaces of the end castings 80 are adapted for spring seats at the same level as the spring seats 6. The springs 10 are disposed in cruciform relation on the end of the spring plank and the seats 6, and it will be noted that the springs on the seats 6 overlap the side edges of the spring plank 85 so that they are carried partly by the spring plank and partly by the side frame. The intermediate connecting member 9 of the spring plank imparts flexibility thereto so that it is better able to resist vertical and 90 torsional stresses.

The brake hanger brackets 11 rise from the sides of the spring plank and a transverse web 12 extends between the brackets over the spring plank to reinforce the structure. In Figures 1, 2 and 3 the brake hanger brackets are shown united integrally with the spring plank while in Figure 4, they 100 are shown secured to the spring plank by rivets 13, the connecting member 9 being also integral with the end castings in Figures 1, 2 and 3 while in Figure 4 said parts are secured together by rivets 14. It will be un- 105

derstood that the brackets may be integral with the end castings to which the connecting member is riveted or vice versa.

Having fully described my invention what I claim as new and desire to secure by Letters Patent, is:—

1. In a car truck, a spring plank supported by the lower member of the side frame between the columns, and springs carried, some wholly on the spring plank and some partially on the spring plank and partially on the side frame adjacent thereto at the bases of the columns, the spring supporting surfaces having the same general level.
2. In a car truck, the combination of a side frame having separated spring seats on its lower portion at the bases of its columns, a spring plank, and means carried by the spring plank and disposed between the spring seats on the side frame, said means affording spring bearings on the same horizontal plane as that of the spring seats on the side frame whereby the springs may bridge the seats on the side frame and the bearings on the spring plank.
3. In a car truck, the combination of a side frame having a bolster opening and having separated spring seats on its lower portion at the bases of its columns, a spring plank, means carried by the spring plank between the spring seats on the frame and affording spring bearings in the same horizontal plane as that of the seats on the side frame, and springs seated partially on the spring seats on the side frame and partially on the spring bearing means carried by the spring plank.
4. In a car truck, the combination of a side frame having a bolster opening and having separated spring seats on its lower portion at the bases of its columns, a spring plank, means carried by said spring plank between the spring seats on the side frame, springs seated partially on the spring bearing means carried by the spring plank, and other springs bearing solely upon the spring bearing means on the spring plank, the lower ends of all the springs being substantially in the same horizontal plane.
5. In a car truck, the combination of a side frame having columns and spring seats at the bases of the columns, and a spring plank having its end disposed between the spring seats, the end of the plank conforming on its under side to the side frame between the spring seats and having its upper surface in the same horizontal plane with the spring seats whereby springs may be supported partly on the spring plank and partly on the spring seats.
6. In a car truck, the combination of a side frame having a concave lower portion,

a spring plank convex on its under side to rest on the side frame and adapted to carry springs on its upper side, and spring seats on the side frame at the sides of the spring plank and flush therewith whereby springs may be carried partly on the spring plank and partly on the side frame adjacent and outside the spring plank.

7. In a car truck, the combination of a side frame having columns, and a spring plank supported by and conforming to the lower member of the side frame between the columns whereby it will be held against movement along the side frame and having its upper surface in a substantially horizontal plane whereby springs may be carried partly on the spring plank and partly on the side frame adjacent and outside the spring plank.

8. In a car truck, the combination of a side frame including upper and lower members, columns connecting said members, and spring seats on the lower member in proximity to the columns, the confronting sides of the columns being vertical in their upper portions to define a bolster opening and converging in their lower portions, and a spring-carrying member supported by the lower member of the side frame between the columns and having its spring-carrying surface on a level with the spring seats on the side frame.

9. In a car truck, the combination of a side frame, and a spring plank comprising an end casting resting in the side frame and of uniform height within the frame and having its top and bottom converging toward its central horizontal plane at the inner side of the side frame, and a relatively flexible portion extending from the inner end of the casting.

10. In a car truck, a spring plank comprising a skeletonized casting supported by the lower member of the side frame between the columns, and adapted to support the springs partially on its upper surface and partially on that part of the frame adjacent to and outside the spring plank.

11. In a car truck, a spring plank comprising a skeletonized casting supported by the lower member of the side frame between the columns and a relatively flexible member extending from the inner end of the casting, the casting being adapted to carry springs on its upper surface, some wholly and some partially on the spring plank, and partially on the side frame adjacent to and outside the spring plank, the spring seats having the same general level.

In testimony whereof, I have signed this specification.

SAMUEL P. BUSH.
